COMBINED AIR CLEANER, INTAKE SILENCER, AND CARBURETOR HOUSING UNIT

Frank Sebok, Detroit, Mich., assignor to Hou-daille-Hershey Corporation, Detroit, Mich., a corporation of Michigan

Application April 11, 1950, Serial No. 155,161

6 Claims. (Cl. 183—20)

1

This invention relates to improvements in a combined air cleaner, intake silencer and carburetor housing unit, and more particularly to such a unit highly desirable for use in connection with a downdraft carburetor associated with an internal combustion engine of the automotive type, although the invention will have other uses and purposes as will be apparent to one skilled in the art.

Extreme difficulty has been experienced in positioning adequate air cleaning and intake silencing equipment beneath the hood of an automobile. The space between the carburetor and the automobile hood has gradually been lessening, and that space will be lessened further to almost an extreme extent in the proposed designs. Heretofore such apparatus, air cleaning and intake silencing means, has been connected to the carburetor by means of clamping elements to join a portion of the apparatus to the carburetor air intake horn, which horn was an integral part of a heavy cast carburetor housing held in place by a number of bolts or the like. The construction of the cleaning and silencing means as well as the construction of the carburetor itself was a distinct detriment to the positioning of the cleaning and silencing apparatus within the limited space provided beneath the hood of an automobile.

It has therefore become desirable to eliminate a material amount of structural elements heretofore believed necessary in order to get the necessary equipment in the space allowed.

In the instant invention, this is accomplished by the provision of a composite air cleaner and intake silencing construction, with an integral part of that structure functioning as a housing for the carburetor, thereby eliminating the previously used heavy cast housing, the intake horn of the carburetor, and the clamping connection between the cleaning and silencing apparatus and the carburetor intake horn.

Other difficulty experienced with previous apparatus of this type, especially in an endeavor to so construct that apparatus that it would fit in the limited space, was the provision of smooth air flow, the maintaining of low restriction to air flow, and the high velocity of the air when it entered the carburetor.

The present invention overcomes these difficulties with the provision of a novel air cleaning structure which provides an even smooth flow of air to the carburetor.

The instant invention also provides a structure eliminating all sharp corners so that restriction is maintained at an optimum level.

2

The instant invention also provides a structure wherein the velocity of the air entering the carburetor is considerably reduced.

Still another desideratum of this invention is the provision of an air cleaning arrangement whereby air is delivered to the carburetor immediately adjacent the ports controlled by the choke valve.

It is also an object of this invention to provide a combination air cleaner and intake silencer unit for ready association with a carburetor, and so constructed that there is almost instant as well as direct communication between a choke valve control port of the carburetor and an attenuating chamber of the silencing mechanism.

Still another object of the instant invention is the provision of an air cleaner and intake silencing unit, wherein a partition is provided which forms a housing for a carburetor, and further serves to guide the incoming air, partially form a path for that incoming air, and partially close off a sound attenuating chamber.

Still another object of this invention is the provision of an air cleaner embodying an inside annular air inlet passage, and an outside annular exit passage for clean air, of considerably greater diameter than the inside passage so that the velocity of the air is reduced, said outside exit passage leading directly to the air intake of a carburetor.

It is still a further object of this invention to provide a combined air cleaner, intake silencer, and carburetor housing unit which surrounds a carburetor and may be positioned so as to extend only a minimum distance above a downdraft carburetor.

While some of the more salient features, characteristics and advantages of the instant invention have been above pointed out, others will become apparent from the following disclosures, taken in conjunction with the accompanying drawing, in which—

Figure 1 is a plan view of a combined air cleaner, intake silencer and carburetor housing unit embodying principles of the instant invention, showing the same associated with a carburetor of the downdraft type; and

Figure 2 is a greatly enlarged part sectional, part elevational view taken substantially as indicated by the line II—II of Fig. 1, looking in the direction of the arrows.

As shown on the drawings:

The illustrated embodiment of the instant invention is shown associated with a carburetor of the downdraft type, and more particularly a carburetor designed to supply a V-8 engine, wherein

the carburetor has two exit passages for a combustion mixture, each leading to certain cylinders of the engine. It is to be understood, however, that the instant invention might equally as well be associated with substantially any form of carburetor, including a carburetor having only a single exit passage for a combustion mixture, governed by a single throttle valve, and wherein the fuel and air are admitted by a single choke valve. In view of the fact that the internal carburetor structure forms no part of the instant invention, only those features of the carburetor necessary to the proper presentation of the instant invention are herein disclosed and described, in short, the carburetor being illustrated rather diagrammatically.

The carburetor chosen by way of example includes a base portion 1 which may be connected to an internal combustion engine in a known manner. This base portion has therein a pair of mixing chambers 2 and 3 leading to opposite sides of a V-8 engine. The exit of the combustion mixture from these mixing chambers is controlled by the usual throttle valves, not shown in the drawings. Entrance of both fuel and air into the mixing chambers is controlled by a pair of choke valves 4 and 5, respectively, both of which are connected to the same shaft 6 for simultaneous operation either manually or automatically.

Above the base portion of the carburetor is a structure 7 housing the customary float chamber, and adjacent that structure is another structure 8 which houses the customary accelerating pump. Liquid fuel emanates from the float chamber to the ports controlled by the choke valves 4 and 5 by way of fuel discharge pipes 9 and 10, respectively.

Extending upwardly from the structure 7 to which it is affixed, is a single bolt 11 which may be equipped at its outer threaded end with a suitable wing nut 12 or the equivalent.

The carburetor is also provided with a housing supporting flange 13 adjacent the top of the base portion 1, and this flange is annularly grooved in its upper face to provide a seat for a gasket 14.

The illustrated embodiment of the instant invention includes a casing comprising separable sections. The lower of these separable sections includes an inside partition 15 having an outwardly and downwardly stepped flange 16 around its open lower end, the horizontal portion of which flange seats upon the aforesaid gasket 14. Obviously, this flange has the same general contour as the supporting flange 13 of the carburetor, and the preferable contour is round for the sake of economy. Immediately above the flange 16, the casing 15 is provided with an annular series of relatively large openings 17 through which air may be admitted to the interior of the casing and thus to the carburetor. The partition or casing 15 has an upwardly domed or peaked top 18, the central portion of which is somewhat flattened and provided with an aperture through which the upper end of the aforesaid bolt 11 may extend, this flattened portion functioning as a seat for the wing nut 12 which is attached externally of the cover 18. Thus, the casing or partition 15 together with its cover 18 forms a very effective housing for the carburetor, enclosing all carburetor structure above the supporting flange 13, and taking the place of the heretofore utilized heavy cast carburetor housing. At this point, it may well be noted that the entire combined air cleaner, intake silencer and carburetor housing unit is held in position over the carburetor by

means of the single bolt 11 and the wing nut 12. When this wing nut is tightened, the inner partition or casing 15 is obviously pressed down into air tight sealing engagement with the gasket 14.

5 In an intermediate location, a cross partition 19 is spot welded or equivalently secured to the inner partition 15 and extends outwardly into similar fixed engagement with a substantially cylindrical shell 20 having an inwardly extending bottom 21, in turn connected to an upwardly extending tube 22 which, as will more fully later appear herein, may function as a tuning tube for an attenuating chamber. The transverse partition 19 is shaped to provide a sump for an air 10 cleansing liquid 23 which may preferably be a relatively light oil. Securely affixed to the intermediate portion of the cross partition 19 is another cross partition 24 which has its outer margin spot welded or equivalently secured to the aforesaid shell 20, this partition together with the partition 19 defining a sound attenuating chamber 25 of relatively small volume, for the attenuation of high pitch or a high frequency sound emanating from the internal combustion engine with which the carburetor is connected. Communication is had with the interior of the attenuating chamber 25 by way of a series of openings 26 through the shell 20. It will be noted that another attenuating chamber 27 of much larger volume, for the 15 attenuation of low frequency sounds is established between the bottom 21 of the shell 20, the partition 24 and the inner portion of the partition 19, communication to which is established by way of the aforesaid tuning tube 22. The length of this tube 22 determines the actual tuning of the attenuating chamber 27. Both the attenuating chambers 25 and 27 function upon the resonator principle.

It will be noted that the tuning tube 22 is concentric with but of greater diameter than the aforesaid partition or casing 15 so that there is a sound passageway 28 therebetween, and this passageway communicates by way of the openings 17 in the casing 15 almost directly with the ports controlled by the choke valves 4 and 5 from which the sound emanates from the engine. Consequently, there is an almost instantaneous silencing of the heavier or predominant tones emanating from the engine, and such sound waves do not have opportunity to travel a long course, be spread, and possibly amplified, before reaching the attenuating chamber.

Enclosing the shell 20 and its bottom 21, but spaced therefrom, is an outer casing or shell 29 having a bottom 30 spot welded or equivalently secured to the casing 15 immediately adjacent the flange 16. Between the shell 20 and the outer casing 29 is an annular passage 31 for clean air which leads directly to the opening 17 in the casing 15 and thus clean air is delivered to the carburetor immediately adjacent the ports controlled by the choke valve. This is deemed highly advantageous for optimum carburetion.

With the exception of a plurality of spring 65 clamps 32, the above described structure includes the lower casing section of the combination unit.

The upper casing section includes a cover 33 having a depending skirt at its outer edge indicated at 34, which is provided with a suitable 70 bead for engagement by the aforesaid spring clamps 32 so that the two casing sections may be joined together. Obviously, a gasket may be interposed between the casing sections to insure an air tight seal.

The cover 33 is provided with a relatively large

central opening 35 defined by a reverse bend in the cover, and just outside that opening, the cover is provided with another skirt portion 36 provided with an annular series of relatively large openings 37 therein which conjointly function as a dirty air inlet. This skirt portion 36 rests against, but is not secured to the aforesaid cover 18 of the casing 15.

Held by a lock seam engagement resulting from the reverse bend in the cover 33 is an inside filter holding shell 38 depending from the cover, and turned inwardly as at 39 to provide a bottom provided with a series of large apertures 40 therein. This shell 38 together with its bottom 39 supports a filter mass 40 preferably of the bonded type and made up of animal hair, vegetable fiber, wavy wire or ribbon, or any other suitable material with adjacent strands bonded together by a suitable agent such as a thermoplastic. Between the filter holding shell 38 and the aforesaid casing 15 is an annular passage 41 which functions as an air inlet passageway, and which leads directly toward the aforesaid liquid sump.

From the foregoing description, it will be apparent that the casing or partition 15 not only effectively functions as an amply sufficient housing for the carburetor, but also functions partially to define the air inlet passageway, and partially to close off a sound attenuating chamber. In addition, the upwardly peaked cover 18 of this partition effectively guides incoming air smoothly and evenly into its proper path 41.

In operation, the instant invention is simple yet highly efficient. It is a simple expedient to connect the combination air cleaning, intake silencing carburetor housing unit over the carburetor by the simple expedient of placing the unit in position, and tightening down the thumb nut 12, the single bolt 11 being all that is necessary to hold the entire unit properly in position. When so mounted, the partition 15 of the unit effectively houses the carburetor. Upon operation of the internal combustion engine with which the carburetor is associated, air is drawn through the device by way of the inlet opening 35, descending against the upwardly peaked cover 18 of the partition 15, passing downwardly through the inlet passageway 41, then passing upwardly after contacting the sump liquid 23 through the filter mass 40, descending the considerably larger passageway 31 where the velocity of the air is considerably reduced by virtue of the size of the passage, and moving substantially radially inwardly to discharge through the opening 17 inside the carburetor housing and immediately adjacent the ports controlled by the choke valves 4 and 5. Thus, there is an extremely smooth and unrestricted passage for air entirely through the apparatus, there being no sharp corners around which the air must turn, but all corners being round as clearly seen in the drawings.

At the same time, it will be noted that sounds of low frequency emanating from the internal combustion engine backwardly through the carburetor, exit through the ports controlled by the choke valves 4 and 5, and those sounds of lower frequency are almost immediately attenuated by their entrance into the large chamber 27. Sounds of higher frequency may pass backwardly through the inlet passageway 31 for cleaned air to enter the attenuating chamber 25 of lesser volume.

In addition it should be especially noted that the entire unit may be disposed substantially as

low as possible over the carburetor, it being only essential to provide sufficient clearance for the unit above the upper end of the accelerating pump structure 8, and the unit may be even lower

5 than disclosed in the drawings, substantially to the extent where the cover 18 of the casing 15 actually contacts the upper end of the accelerating pump structure. Thus, the combination air cleaning, intake silencing and carburetor housing 10 may be disposed in a minimum clearance between the top of the carburetor and the engine hood, and substantially the same clearance as heretofore required for the old fashioned casting type of carburetor housing. It should also 15 be noted that there is no need for any air intake conduit connection by way of expensive clamping means to unite that conduit with the air intake horn of the carburetor, because the latter is also completely eliminated.

20 It will be understood that modifications and variations may be effected without departing from the scope of the novel concepts of the present invention.

I claim as my invention:

25 1. In combination, a carburetor having a supporting flange adjacent a port unenclosed by a carburetor structure and controlled by a choke valve and an air cleaning and intake silencing unit connected with said carburetor, said unit 30 including an inner casing seated on said supporting flange to house said carburetor and having an opening adjacent said flange, an outer casing spaced from said inner casing and having an air inlet opening therein, means between said casings 35 defining an air path between said openings, air cleaning means in said path, and partition means between said casings defining with said inner casing a sound attenuating chamber operable upon the resonator principle to silence the fundamental tone of the engine carrying the carburetor, there being an opening for sound waves to said attenuating chamber immediately adjacent the opening in the inner casing.

40 2. In combination, a carburetor having a supporting flange adjacent a port controlled by a choke valve and an air cleaning and intake silencing unit connected with said carburetor, said unit including an inner casing seated on said supporting flange to house said carburetor and 45 having a clean air outlet opening adjacent said flange, an outer casing spaced from said inner casing and having an air inlet opening therein, means between said casings defining an air path between said openings, air cleaning means in said path, said path being of greater cross-sectional area on the outlet side of said cleaning means to reduce the velocity of the air prior to its discharge through the outlet opening, and partition 50 means associated with the first said means defining a sound attenuating chamber operable upon the resonator principle with an opening for sound waves immediately adjacent said clean air outlet.

60 3. In combination, a carburetor having a supporting flange adjacent a port controlled by a choke valve and an air cleaning and intake silencing unit connected with said carburetor, said unit including an inner casing seated on said supporting flange to house said carburetor and 65 having an air outlet opening adjacent said flange, an outer casing spaced from said inner casing and having an air inlet opening therein, means between said casings defining an air path between said openings, air cleaning means in said path, and means between said casings defining a sound 70

attenuating chamber separate from the air path and operable upon the resonator principle communicating with said air path substantially at its junction with said outlet opening.

4. In an air cleaning and carburetor housing unit, an inner casing having a closed top and of a size to enclose a carburetor, an outer casing having its side wall spaced from said inner casing, said outer casing having an air inlet opening in its top above the closed top of the inner casing, filter holding shells between said casings defining a path communicating with said inlet around said inner casing and a path for cleaned air between the shells and outer casing wall whereby the path for cleaned air is larger and the clean air travels at less velocity than entering dirty air, partition means in said casing defining a sound attenuating chamber of the resonator type, and said chamber communicating with said clean air path and said clean air path communicating with the interior of the inner casing at the lower end of said inner casing.

5. In a combined air cleaning, intake silencing and carburetor housing unit, an outer casing having an air inlet, an inner casing of a size to receive therein the upper part of a carburetor and act as a protective housing for operating parts of the same, spaced filter holding shells between said casings and defining therewith separate air paths one for dirty air and one for cleaned air, partition means defining a sound attenuating chamber of the resonator type to attenuate the fundamental tone of the engine with which the unit is to be associated, said inner casing having an opening through which air is delivered from the cleaned air path, and said partition means

having an opening to said attenuating chamber adjacent said clean air delivery opening in the inner casing.

6. In an air cleaning unit, an inner casing having a closed top, an outer casing of greater cross-sectional area around the inner casing, said outer casing having an inlet for dirty air adjacent the closed top of said inner casing, means between said casings defining therewith a path for incoming air and a path of greater cross-sectional area for outgoing clean air, air cleansing means between said paths, whereby clean air may leave the unit at less velocity than incoming dirty air enters the unit, said inner casing being of a size to receive therein the upper part of a carburetor and act as a protective housing for operating parts of the carburetor, partition means between said casings defining a sound attenuating chamber of the resonator type to attenuate the fundamental tone of the engine with which the unit is to be associated, and said inner casing and said partition means having adjacent openings near the bottom of the inner casing communicating with the clean air path and said chamber.
